PHOTOGRAPHIC MEANS FOR RECORDING SOUND

Filed May 18, 1925

*Inventor;
Russell Hart,*

per Arthur J. Farnsworth,
Attorney.

UNITED STATES PATENT OFFICE.

RUSSELL HART, OF LOS ANGELES, CALIFORNIA.

PHOTOGRAPHIC MEANS FOR RECORDING SOUND.

Application filed May 18, 1925. Serial No. 31,251.

To all whom it may concern:

Be it known that I, RUSSELL HART, a citizen of the United States, residing at Los Angeles, in the county of Los Angeles and 5 State of California, have invented a new and useful Photographic Means for Recording Sound, of which a specification is set forth below.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

20 My invention relates to photographic means for recording sound and its principal objects are; first, to provide means for projecting an exceedingly thin beam of actinic rays upon a movable photo-sensitized film; second, to afford facilities for vibrating the beam telephonically so as to produce a continuous sound record upon the film when the latter is given a uniform motion; and, third, to accomplish the above by means of apparatus of great simplicity.

My objects are attained in the manner illustrated in the accompanying drawings, in which—

Figure 1 is a fragmentary plan view of 35 one form of my invention, in which certain parts are shown in section;

Figure 2 is an elevation of the above construction, shown partly in section and with a portion of the camera box removed;

40 Figure 3 is an elevation of a short section of film on which a sound record has been recorded in the manner to be described hereafter; and

Figure 4 is an elevation of a satisfactory type of light source for use in connection with my invention.

Similar reference numerals refer to similar parts throughout the several views.

My apparatus comprises a suitable base 5 adapted for mounting on a camera in any convenient manner as by a bracket and screw holes 6. Upon an extension of the base is mounted a relatively large sprocket drum

7 with sprockets 8 adapted for engaging a 55 moving picture film 9. There are also a pair

of rollers 10 for guiding the film. These parts are all within a light-proof camera box of which a portion of the wall is shown at 11. Outside of the camera box is a magnet 12 which may be either a permanent magnet or an electro-magnet, as indicated in Fig. 2. This magnet has opposed bifurcated poles, the opposed faces of which are slightly spaced. In the form depicted one pair of the pole branches 13 and 14 are integral with the magnet frame. The other pair of pole branches 15 and 16 are adjustable by means of screws 17 so that the gap between their faces may be varied. In this manner it is possible to compensate for the different 60 lengths of the magnetic circuits through the pole bifurcations, so that approximately the same magnetic flux may be made to pass between each pair of pole faces. That is to say, the flux through the gap between poles 13 and 14 may be made to closely approximate the flux through the gap between pole faces 15 and 16. In certain cases it may be advisable to make the poles of both pairs of bifurcations adjustable.

80 A small cylindrical armature 18, intermediately pivoted at 19, is mounted centrally in such a manner that its extremities are in the respective magnetic fields of the bifurcated magnet poles. This armature 85 carries a small cylindrical mirror 20 coaxially mounted upon its upper extremity. The purpose of this mirror will be explained presently.

Surrounding the armature in an energizing 90 coil 21 adapted by means of its terminal wires 22 to be connected into a telephonic circuit.

It will be noted that the two pole bifurcations on each side of the armature are of the 95 same polarity. That is, both pole bifurcations on the left are either north or south and on the right are either south or north. When coil 21 is energized one pole of the armature becomes north and the other 100 south and therefore the magnetic attractions of the bifurcated poles cooperate in causing it to swing about its pivot. Changes and reversals of current in coil 21 obviously cause the armature to vibrate in consonance therewith at variable frequency and amplitude corresponding in the characteristics of the telephonic current.

105 The armature is prevented from contacting with the pole faces by means of resilient 110

material 23 crowded in between the armature and one or both pairs of pole faces. This material also damps the armature movements in a manner that has been found 5 in practice to be highly desirable for sound recording. I have found that sponge rubber is an excellent material to use for this purpose and it may be variably compressed by crowding into the spaces between the 10 armature and pole faces or by adjusting the width of the gap between armature and pole faces, as may be most desirable.

Intermediate cylindrical mirror 20 and film 9 is a lens tube 24, adjustably mounted 15 in a bracket 25 and extending through wall 11 of the camera box. This tube is longitudinally slidabie so that a secondary image of a primary image thrown upon the mirror, may be focused by means of lenses 26 upon 20 the film in a direction normal to its surface. The set screw 27 maintains the focus when the adjustment is complete.

For the light source I prefer to employ a lamp of the type shown at 28 having a thin 25 rectilinear filament 29 and mounted vertically in any convenient manner as by means of base 30. If a lamp of this character is positioned approximately as shown in Fig. 1, its rays 31 will fall upon cylindrical mirror 20 and be reflected in the form of a much attenuated primary image in the direction of 30 lenses 26. The latter may be made to focus a sharp secondary image, which may be further attenuated, upon the film at 32. In 35 this manner the actinic rays falling upon the film are made to take the form of an exceedingly thin beam of light which is vibratile in the direction of motion of the film. Vibratory movements of the armature and mirror therefore may be made to expose a longitudinal strip upon the moving 40 film and if the movement of the film is uniform, and the vibrations are produced telephonically, the film when developed will 45 show a sound record of the character shown at 33 in Fig. 3.

The sound record comprises a series of 50 variably spaced parallel lines of variable density. The spaces between the lines are also slightly exposed and of variable density.

For reproduction of the recorded sound 55 the film is made to pass at a uniform speed, corresponding to the recording speed, in front of a suitable photo-electric cell and a tenuous beam of light is caused to pass through the record and impinge upon the cell. There are various known means for reproduction in this manner and the reproduction 60 is not a part of the present invention and not claimed herein.

The film is preferably driven at a uniform 65 velocity by means of the sprocket drum 7, and the latter is relatively large and fairly heavy so that its inertia may exert an appreciable effect in maintaining a uniform

motion of the film during the recording. This arrangement is far better than running the film through an exposure gate for the reason that it completely eliminates chattering or vibration of the film by reason of 70 its being pulled through such gate. Vibrations of this character of course produce stray noises and injure the quality of the sound record. Moreover the large sprocket drum 7 accurately positions the film during 75 the recording process.

Having thus fully described my invention in a manner that will be clear to those familiar with the art concerned, I claim:

1. Photographic sound recording means 80 comprising; a uniformly moveable photo-sensitized film; a light source; and a cylindrical mirror, vibratile to sound, whereby an attenuated image of said source may be thrown upon said film transversely to its direction of motion.

2. Photographic sound recording means 90 comprising; a uniformly movable photo-sensitized film; a rectilinear light source; a cylindrical mirror, vibratile to sound, adapted to reflect an attenuated image of said source; and a lens intermediate said mirror and said film, whereby an attenuated secondary image of the first said image may be projected upon said film transversely to its direction of motion.

3. Photographic sound recording means 100 comprising; a uniformly movable photo-sensitized film; an illuminable rectilinear filament of great tenuity; a cylindrical mirror, vibratile to sound, adapted to reflect an attenuated image of said filament; and a lens intermediate said mirror and said film, whereby an attenuated secondary image of the first said image may be focused upon said film transversely to its direction of motion.

4. Photographic sound recording apparatus 105 comprising; a uniformly movable photo-sensitized film; an illuminable rectilinear filament; a cylindrical mirror, vibratile to sound in a plane parallel to the film, adapted to reflect an attenuated image of said filament; a lens intermediate said mirror and said film, whereby an attenuated secondary image of the first said image may be focused upon said film transversely to its direction of motion; and telephonic means 110 for vibrating said mirror.

5. Photographic sound recording apparatus 115 comprising; a uniformly movable photo-sensitized film; an illuminable rectilinear filament; an armature in a constant magnetic field, adapted to vibrate in a plane parallel to the film; a coil adapted for variably magnetizing said armature; a cylindrical mirror mounted upon said armature and adapted to reflect an attenuated image of said filament; a lens intermediate said mirror and said film, whereby an attenuated secondary image of the first said image may 120 125 130

be focused upon said film transversely to its direction of motion; and means for energizing said coil by a telephonic current.

6. Photographic sound recording apparatus comprising; a uniformly movable photo-sensitized film; an illuminable rectilinear filament; an intermediately pivoted armature having its extremities in constant magnetic fields of the same flux direction, 10 and adapted to vibrate in a plane parallel to the film; a coil surrounding said armature adapted for variably magnetizing it; a cylindrical mirror mounted upon an extremity of the armature co-axial therewith, 15 and adapted to reflect an attenuated image of said filament; a lens intermediate said mirror and said film, whereby an attenuated secondary image of the first said image may be focused upon said film transversely to its direction of motion; 20 and means for energizing said coil by a telephonic current.

7. Photographic sound recording apparatus comprising; a uniformly movable photo-sensitized film; an illuminable rectilinear filament; means for producing a pair of constant magnetic fields, parallel to each other and of the same flux direction; an intermediately pivoted armature having its respective extremities in said fields, and adapted to vibrate in a plane parallel to the film; 25 a coil surrounding said armature adapted for variably magnetizing it; a cylindrical mirror mounted upon an extremity of the armature co-axial therewith, and adapted to reflect an attenuated image of said filament; 30 a lens intermediate said mirror and said film, whereby an attenuated secondary image of the first said image may be focused upon said film transversely to its direction of motion; 35 and means for energizing said coil by a telephonic current.

8. Photographic sound recording apparatus comprising; a uniformly movable photo-sensitized film; an illuminable rectilinear filament; a magnet having opposed bifurcated poles with gaps between the respective opposed pole faces; an interme-

diate pivoted armature having its respective extremities in said gaps, and adapted to vibrate in a plane parallel to the film; a 50 coil surrounding said armature adapted for variably magnetizing it; a cylindrical mirror mounted upon an extremity of the armature co-axial therewith, adapted to reflect an attenuated image of said filament; a lens intermediate said mirror and said film, whereby an attenuated secondary image of the first said image may be focused upon said film transversely to its direction of motion; 55 and means for energizing said coil by a telephonic current.

9. The construction set forth in claim 8 in combination with means for varying the width of the gap between opposed pairs of the magnetic pole faces. 60

10. The construction set forth in claim 8 in combination with; means for varying the width of the gap between opposed pair of the magnetic pole faces; and resilient packing between the armature and pole faces 65 whereby the armature is prevented from contacting with the pole faces and its vibratory movements are damped. 70

11. Photographic sound recording apparatus comprising; a rotatable sprocket drum; a uniformly movable photo-sensitized film bent around said drum and engaging said sprockets; a light source; and a cylindrical mirror, vibratile to sound, whereby an attenuated image of said source may be thrown 75 upon the portion of the film engaging the drum, transversely to its direction of motion. 80

12. Photographic sound recording apparatus comprising; a relatively large and uniformly rotatable sprocket drum; a photo-sensitized film bent around said drum and engaging said sprockets; a rectilinear light source; and a cylindrical mirror, vibratile 85 to sound, whereby an attenuated image of said source may be thrown normally upon the portion of the film engaging the drum, 90 transversely to its direction of motion.

RUSSELL HART.
